UNITED STATES PATENT OFFICE.

JOSEPH LANDKAMER, OF WILLIAMSPORT, PENNSYLVANIA.

ADJUSTABLE CHAIR.

SPECIFICATION forming part of Letters Patent No. 788,656, dated May 2, 1905.

Application filed June 13, 1903. Serial No. 161,350.

To all whom it may concern:

Be it known that I, JOSEPH LANDKAMER, a citizen of the United States, residing at Williamsport, in the county of Lycoming and State 5 of Pennsylvania, have invented a new and useful Adjustable Chair, of which the following is a specification.

My invention is an improvement in adjustable chairs, and has for its object to provide a 10 reclining-chair comprising a seat, back, and foot-rest all pivotally connected to and swinging independently of the supporting-legs of the chair and adapted to accommodate themselves to the position naturally assumed by the 15 body of the user instead of the user arranging his position with reference to the inclination of the parts comprising the chair, the various parts of the chair practically balancing each other.

20 My invention consists of the novel features of construction and combination of parts hereinafter described, particularly pointed out in the claim, and shown in the accompanying drawings, in which—

25 Figure 1 is a perspective view of a chair embodying my improvements. Fig. 2 is a side elevation of same, the parts being in their normal position. Fig. 3 is a side elevation, the parts being in the position assumed when 30 a person reclines in the chair. Fig. 4 is a perspective view showing the head-rest and means for adjusting the same. Fig. 5 is a detail perspective view showing the rear of the chair-frame. Fig. 6 is a section through the bracket seen in Fig. 5. Fig. 7 is a perspective view 35 of the forward portion of one of the chair-arms. Fig. 8 is a detail view of the standard supporting the front portion of the chair-arm. Fig. 9 is a perspective view showing in out- 40 line the upper end of the foot-rest hanger pivoted to the side of the chair-seat. Fig. 10 is a similar view of the upper end of one of the front legs of the chair. Fig. 11 is a detail view, partly in section, showing the manner 45 of hinging the foot-rest.

In the above-described drawings I have shown my improvements in connection with a chair having rockers. It will be understood, however, that the parts to be now described

may be combined in a chair without rockers, 50 if so desired.

On the rockers A are mounted the front and rear legs B B', and the legs B are cut away at their upper ends, as shown at B², and notched in front adjacent the rocker, as at B³. The 55 legs B' are pivoted at their upper ends to the sides of the chair-back C at a point above the seat C'. The seat is hinged to the back of the chair at C², and the sides of the seat are pivoted adjacent the front of the seat to hangers 60 D, as at C³, which extend above the seat, and in turn are pivoted to the front legs of the chair adjacent their upper ends, as shown at D', the hangers being cut away or reduced at 65 their upper ends, as shown at D², said cut-away portions lying opposite the cut-away portion B² of the front legs, and between the two are pivoted the lower ends of the arm-standards E. The lower ends of the hangers D are connected by a cross-bar D³, the ends 70 of which extend through the hangers and engage the notches B³ when the parts are in the position shown in Figs. 1 and 2.

A foot-rest D⁴ is hinged at D⁵ to the bar D³ in such a manner that it can be folded up 75 against the bar, if desired, as shown in Fig. 11. Brace-bars D⁶ are also employed to complete and strengthen the hanger-frame. The upper ends of the standards E are threaded and fit into balls E', which are arranged in 80 metal sockets E², secured to the under side of the chair-arms adjacent their front ends. These chair-arms F rest against and are hinged to the sides of the chair-back, as shown at F'. A head-rest G is secured to the upper end of 85 the chair-back by the hinges G'. Brackets H H' are secured to the rear of the chair-seat and head-rest, respectively, and rods H² and H³ are pivoted to arms of the respective brackets, the adjacent ends of the rods being 90 connected by a turnbuckle H⁴.

From the above it will be seen that the seat C' is hinged at the rear to the back C, which is pivoted to the rear legs of the chair above the seat, and that the front portion of the seat 95 is pivoted to the hangers D, which are pivoted to the front legs of the chair at a point above the seat. The seat is thus pivotally

suspended, and the back, foot-rest, head-rest, and arms all have movement independent of the seat and relative thereto.

Having thus fully described my invention, 5 what I claim as new, and desire to secure by Letters Patent, is—

An adjustable chair having supporting-legs, hangers pivoted to the upper ends of the front legs, arms pivoted to said front legs and hangers, the lower ends of the arms spacing the hangers from the legs, said arms having balls 10 at their upper ends, side arms having sockets

adapted to receive said balls, a back pivoted between the rear legs and extending below the upper ends of said legs, a seat hinged at the 15 rear to the back and pivoted at the front to the hangers at points below the upper ends of the front legs, the said side arms being hinged at their rear ends to the back, and a foot-rest carried by the hangers.

JOSEPH LANDKAMER.
